UNITED STATES PATENT OFFICE.

JAMES L. SCHAEFFER, OF HARRISBURG, PENNSYLVANIA.

FINGERING ATTACHMENT FOR FLUTES.

SPECIFICATION forming part of Letters Patent No. 307,807, dated November 11, 1884.

Application filed August 24, 1883. (No model.)

To all whom it may concern:

Be it known that I, JAMES L. SCHAEFFER, a citizen of the United States, residing at Harrisburg, in the county of Dauphin and State of Pennsylvania, have invented certain new and useful Improvements in Fingering Attachments for Flutes and other Musical Instruments; and I do hereby declare that the following is a full, clear, and exact description 10 of my said invention, which will enable others skilled in the art to which it appertains to make and use the same, reference in said description being had to the annexed drawings, making a part of this specification.

15 Heretofore certain well-known difficulties existed in the fingering required of the left hand in rendering certain notes of the chromatic scale on the old flute; hence various attachments to the same have been made from 20 time to time, giving rise to new systems of fingering or playing more or less complicated.

25 My invention is an original device specially adapted for producing the notes or tones A $\flat$, B $\flat$, and C $\sharp$, and consequently, by allowing certain of said three keys to be open, perfecting the intonation of several of the higher tones, thus making the old or common flute as 30 perfect in intonation and as easy to finger as can be desired. My said device is simply a 35 fingering mechanism, which in the drawings is shown attached to the left-hand joint of the flute or next the blow-section of the instrument; but my improved device is also applicable to the right-hand joint and to other musical instruments of similar character, as the clarionette and the hautboy.

40 Some advantages of my improvement may be explained as follows: On the common flute it is necessary to employ the little finger of the left hand in manipulating both the keys F $\sharp$ and A $\flat$. In my invention it is not necessary to employ said finger in the making A $\flat$, thus leaving it free to be used in making F $\sharp$ only, and thus avoiding double or difficult duty 45 by it.

45 The most decided advantage to be obtained from my invention is the execution of the keys ranging from B $\flat$ to D $\flat$ and G $\flat$, and in sharps ranging from A to B and F $\sharp$ keys, making 50 their execution almost as easy as the keys of C, G, and D. These advantages are so obvious to all familiar with the difficulties in flute-

playing that a fuller explanation thereof is deemed unnecessary.

It is true Behm did improve the old flute by 55 piercing the holes thereof in their more correct positions and by employing his own peculiar keys. His object was not, primarily, to facilitate the fingering, but to make the tones more correct. While his fingering devices did afford a very great degree of facility, still many difficulties remained, which my invention entirely removes, prominent among which is my superior means for obtaining B $\flat$.

60 The novel and useful features of my invention comprise, first, a fingering attachment for musical instruments, employing as mechanism to facilitate the producing of certain musical notes or tones a rock-shaft provided on its left end with a plate or lever for rocking it by the 65 direct application of the thumb of the left hand, a key fixedly attached to the right end of the same and mounted on the middle portion of said shaft, certain keys loosely sleeved thereon, but coupled with said fixed key to be 70 controlled thereby when the the thumb-plate is depressed, and to be operated by other fingers than the thumb, either individually or collectively when said thumb-plate is not depressed; 75 second, a rock-shaft extended to command a 80 number of keys provided with a thumb-plate and a fixedly-attached key on its ends, in combination with several rotary sections loosely sleeved on the intermediate portion of said shaft, each of said sections having a key as 85 part thereof, and with certain tenons and abutments on said sleeves for connecting them with each other and with said end key to secure 90 their control thereby, and with certain springs for retracting the keys to make them all stand 95 open when the thumb is off said plate; third, the means of an extended rock-shaft provided with thumb-plate and key both fast on its ends, and several keys loosely sleeved on its middle, the same having connecting projections on them and retracting-springs, all 100 co-operating as a means of controlling said keys collectively, in combination with a number of secondary keys in communication with and controlling said intermediate keys to produce 105 certain musical notes and tones when the thumb is off the plate; fourth, the combination of certain grouped and coupled keys and means for operating them, as hereinafter set forth.

In the further description reference is had to the accompanying drawings, in which Figure 1 represents a perspective view of a left-hand joint of a flute with my fingering attachment on it. Fig. 2 represents a plan of the same with the keys closed, as when thumb-piece is depressed. Fig. 3 represents a right end view of the same. Fig. 4 represents a cross-section taken at line a, Fig. 2. Fig. 5 represents a sleeve-joint enlarged as on rock-shaft. Fig. 6 represents a secondary group coacting with certain keys on main rock-shaft. Fig. 7 represents a front view of the main rock-shaft and its connected parts detached from the flute. This is the main controlling leverage of my attachment. Fig. 8 represents the thumb-lever or rock-shaft with fixed key-joint thereon.

Similar letters of reference and musical signatures denote similar parts throughout all the views.

Letter H denotes a left-hand joint of a flute, and R its splices.

K M N P denote the main shaft-mountings.

W W' denote the secondary mountings.

K denotes the thumb-plate, made fast on shaft S², which latter has on its opposite end the cylindrical section P, made fast on same. The section P has on it the key A₂, which it operates. The intermediate sections, M N, on said shaft S² are loose sleeves, limited, however, in their movements as follows: Section P has a tenon, N', on it, which enters a cut, M', on section N, and section M is likewise coupled with section N. Said sections are free to move to an extent equal to the difference between the breadth of said tenons N' and said cuts M'. The shaft S² is journaled in pillars a, b, d, and d', and the sections M N P couple in pillars d e. Springs m n are attached, as shown, to retract said sections M N P, and through the latter thumb-plate K, so that the keys C, B₂, and A₂ on said sections stand open when the thumb is off said plate K. The section P, actuated by spring m, actuates section N, and it actuates section M when the thumb is on plate K, thus closing all simultaneously. The tubes W W' are mounted freely on a shaft fixed in pillars k l p. Said tubes or sections have on them the levers T T', with key rings attached for the fingers, as shown, and marked, respectively, A₂ and G. The said tubes are actuated by springs like the springs m on the other shaft-mountings. Said springs act to govern said rings when the thumb is on plate K. The levers T T' on sections W W' engage catches S S', respectively, on sections M N. When ring G is depressed, lever T' rotates section N, and it rotates section M. Thus both the keys C and B₂ may be closed, while key A₂ is left open. When the ring A₂ is depressed, lever T rotates section M, and the key C thereon is closed, while keys B₂, A₂, and G are

open. When both keys A₂ and G are depressed, keys C and B₂ are closed, and key A₂ is open, with thumb off plate K.

The results of the above manipulations are these: With A₂ and G fingers shut, the thumb controls A₂ key only; with G finger off the ring the thumb controls B₂ as well as A₂ key. The same with A₂ finger and C key—that is, with finger off ring A₂ the thumb controls key C as well as A₂ and B₂, while the fingers control the keys of C and B₂ separately when thumb is off plate, as above stated.

The trill-keys L L' are operated exactly like the ring-keys A₂ and G, and with their corresponding fingers.

I do not limit myself to the means specified for coupling the sections M N, as other equivalent means may be employed.

What I claim is—

1. A fingering attachment for facilitating the execution of certain notes or tones on flutes, consisting of rock-shaft S², provided with thumb appliance or lever K' at left end, and with key A₂ affixed to its right end, keys B₂ and C, attached to tubes M N, which latter are loosely sleeved on the middle portion of said shaft, and ring-levers G and A₂, coupled and operating substantially as and for the purposes set forth.

2. The device of a fingering attachment for flutes, consisting of the equipped lever or rock-shaft K' P S², provided with key A₂, rotating sections M N, bearing the keys B₂ and C, and separately controlled by ring-levers A₂ and G, substantially as and for the purposes set forth.

3. The co-operating means of the equipped thumb-lever K P S² A₂, provided with the sections M N, loosely sleeved thereon, and coupled by their tenons and abutments N' M' with each other and with right end of said lever, and retracted by springs m, in combination with secondary keys A₂ and G, arranged and connected therewith to effect the separate control of keys C and B₂, substantially as herein set forth.

4. In a transposing-flute or other analogous musical instruments, a fingering attachment for facilitating the execution of music, employing, as an essential part thereof, an extensive rock-shaft provided at its left end with an appliance for rocking it by the left thumb, on its right end with a key fixedly attached thereto, and having two or more keys secured to sleeves loosely mounted on said shaft thereby, in combination with trip-levers for operating one or more of said loosely-mounted keys at a time, when the thumb is off said appliance, substantially as and for the purposes set forth.

JAMES L. SCHAEFFER.
